HENRY HANNEN, OF PHILADELPHIA, PENNSYLVANIA, ASSIGNOR TO S. A. HANNEN AND S. W. GREENE, OF THE SAME PLACE.

Letters Patent No. 64,763, dated May 14, 1867.

IMPROVEMENT IN THE MANUFACTURE OF CARBONATE OF LEAD.

The Schedule referred to in these Letters Patent and making part of the same.

TO ALL WHOM IT MAY CONCERN:

Be it known that I, HENRY HANNEN, of Philadelphia, Pennsylvania, have invented an Improvement in the Manufacture of Carbonate of Lead; and I do hereby declare the following to be a full, clear, and exact description of the same.

My invention consists of a mode or process, fully described hereafter, of producing a pure carbonate of lead.

In order to enable others skilled in the art to practise my invention, I will now proceed to describe a mode of carrying the same into effect, reference being had to the accompanying drawing, which forms a part of this specification, and in which—

Figure 1 is a vertical section of apparatus which may be used for carrying my invention into effect.

Figure 2, a rear view partly in section; and

Figure 3, a sectional plan.

A A are the side walls; B the rear wall, and C is the top of a case or chamber in which fits a series of detachable trays, D D, and a drawer, D', the fronts *f* of the trays and drawer forming, when closed, the front of the chamber. The bottoms *h* of the trays D D are perforated, or consist of slats, or are otherwise formed so as to retain flakes or scraps of lead which are placed in the same, and yet allow of the free passage to and through the mass of flakes of currents of gases. At the rear of the chamber is a vertical pipe, *a*, with which communicate pipes *c c*, each of the latter extending into the chamber above one of the trays D, and being bent, as shown in the drawing, the two parallel portions of each pipe having in the same numerous small or capillary perforations, for a purpose described hereafter. Each of the pipes *c* is closed at the outer end. The pipe *a* is also closed at its upper end, and in the present instance communicates at the lower end with a force-pump, *d*, or its equivalent. Through the top of the chamber passes a tube, *e*, which communicates with a reservoir containing carbonic acid gas; and above the drawer D is a steam pipe, *i*, which is bent to a zigzag or other suitable form, and which communicates with an adjacent steam boiler. Each of the pipes *a c e i* is provided with a suitable valve or cock, by means of which the passage of fluid through the same may be regulated. In the walls of the chambers are windows or glass-covered openings, through which the attendants may observe the materials being operated on within the chamber, and thus ascertain their condition. The lead which is to be converted into a carbonate is first divided into extremely thin flakes, in a manner which it will be unnecessary to describe here, as it forms the subject of a separate application for Letters Patent. The flakes of lead are placed loosely upon the trays D D, and the latter and the drawer D' are introduced into the chamber, as shown in fig. 1, after which steam is passed into the pipe *i*, so that the contents of the chamber are maintained at a uniform temperature of from 100° to 180°. The pump is now placed in communication with a vessel or reservoir containing water, either pure or slightly acidulated with acetic acid, and which is impregnated with chlorine, it being preferable that the liquor should be of the same temperature as the contents of the chamber. The piston is now operated so as to force the liquid into the pipes *a c*, from which it is discharged in the form of a fine spray, through the perforations in the pipe, so as to be thrown directly on to the lead in the trays, both above and beneath each pipe, the entire mass of metal being thus thoroughly moistened. After sufficient water has been discharged on to the metal the action of the pump is arrested until an oxide has been formed on the surface of the metal. The pump is then placed in communication with a vessel containing dilute acetic acid, and the latter is then discharged in sprays from the pipes *c* and on to the oxidized metal, in the same manner as the water. The operation of the pump is again arrested, and as soon as an acetate of lead is formed by the action of the acid on the metallic-oxide, the chamber is filled with carbonic acid gas, which is introduced through the pipe *e*, and which is maintained under a pressure within the chamber, by any suitable means, until the acetate of lead is converted into a carbonate. The above-described operations are then repeated as often as may be necessary to convert all the metallic lead into a carbonate. From time to time during the operation the trays D are agitated, so that the particles of carbonate may be detached from the lead and fall into a drawer, D', which is withdrawn and its contents removed as often as necessary.

In the manufacture of white lead, (incorrectly termed carbonate of lead,) it has heretofore been customary

to introduce into a chamber containing coiled strips or sheets of metallic lead, the vapors of water and acetic acid, and carbonic acid gas, by which the lead is first oxidized, then converted into an acetate, and then into a hydrocarbonate, the production of a true carbonate under such circumstances being impossible. Paints made from the hydrocarbonate of lead become discolored within a greater or less time after their application to the surface of any object, in consequence of the affinity of the hydrocarbonate for gases in the atmosphere with which it will combine, forming colored compounds. As, however, carbonate of lead has no such affinities, paints made from the same will not become discolored, and it is therefore much superior to the hydrocarbonate, not only when used as a pigment, but when applied to various other purposes.

I have found, by repeated experiments, that by discharging the water and acid directly on to the metal, instead of passing them in the form of a vapor into and filling the chamber, not only is the metal more effectively moistened, but the carbonic acid gas is permitted to come into such rapid, direct, and intimate contact with the metal that it is impossible for a permanent hydrate to form, and a carbonate of lead is produced. I have also found that chlorine introduced into the chamber during the transformation of the lead tends to prevent, when properly applied, the formation of a crystalline salt, and that, owing to its bleaching action, a much purer and whiter product is obtained than could otherwise be produced. Care should be taken, however, not to introduce an excess of chlorine, the quantity being regulated by the judgment of the operator. When the carbonic acid gas in the chamber is under a pressure it will combine with the oxide of lead more quickly and intimately than when no such pressure is maintained. The oxide of lead, generally termed "dross," which forms on the surface of lead when the latter is melted for casting and other purposes, and which has hitherto been considered an almost refuse material, may be utilized by introducing it into the chamber on the trays D, and heating it in the same manner as the metallic lead, a carbonate as perfect as that formed from the metallic lead being the result.

Without confining myself to any particular form of apparatus, or to the precise mode of operation above described, I claim as my invention, and desire to secure by Letters Patent—

1. The manufacture of carbonate of lead by the action, upon metallic lead, or oxide of lead, of water, acetic acid, and carbonic acid gas, when the said fluids are brought in contact with the lead, substantially as described:

2. Subjecting the lead to the action of carbonic acid gas under a pressure, substantially as and for the purpose set forth.

3. Subjecting the lead, during the process of its conversion into a carbonate, to the action of chlorine, for the purpose specified.

In testimony whereof I have signed my name to this specification in the presence of two subscribing witnesses.

HENRY HANNEN..
